(57) **ABSTRACT**
A wear resistant component includes a matrix portion made of metal, and a framework portion that is embedded in the matrix portion and is higher in hardness than the matrix portion. The framework portion has a three-dimensional lattice structure formed with a plurality of bar-shaped members, and has a shape that follows a shape of at least a portion of a surface of the matrix portion.

wear resistance of the wear resistant component is improved. As such, according to the wear resistant component of the present disclosure, a wear resistant component with improved wear resistance can be provided.

In the above wear resistant component, at least some of the bar-shaped members may have distal ends exposed on the surface of the matrix portion. This enables the framework portion to contribute to suppression of the progress of wear from the beginning of the wear progression. Further, in the case of producing the wear resistant component by casting, it is readily possible to place the framework portion in an appropriate position by bringing the distal ends (end faces) of the bar-shaped members constituting the framework portion into contact with a wall surface defining a mold cavity to thereby support the framework portion, and then pouring the metal constituting the matrix portion in a molten state.

In the above wear resistant component, the matrix portion may include a distal end region that tapers toward a distal end. The framework portion may be arranged in the distal end region and may have a shape corresponding to an external shape of the distal end region. This can effectively suppress the wear of the distal end region.

The above wear resistant component may further include a core that is arranged inside the framework portion and is higher in hardness than the framework portion. With this, even if the framework portion wears down, the core having an even higher hardness can suppress the progress of wear. Further, with the core being arranged inside the framework portion, in the case of producing the wear resistant component by casting, the metal constituting the matrix portion can be poured in a molten state in the state where the core is supported by the framework portion in the cavity. This facilitates placing the core in an appropriate position.

In the above wear resistant component, the core may have a shape that follows a shape of at least a portion of the surface of the matrix portion. This suppresses the progress of local wear in the region where the core has a shape that follows the surface of the matrix portion.

In the above wear resistant component, the core may have a shape corresponding to an external shape of the framework portion. This can effectively suppress the wear of the framework portion.

SPECIFIC EMBODIMENTS

Specific embodiments of the wear resistant component of the present disclosure will be described below with reference to the drawings. In the drawings referenced below, the same or corresponding portions are denoted by the same reference numerals and the description thereof will not be repeated.

Embodiment 1

First, a tooth of Embodiment 1 as an example of the wear resistant component according to the present disclosure will be described with reference to FIGS. 1 to 5. FIG. 1 is a schematic perspective view showing the appearance of a tooth in Embodiment 1. FIG. 2 is a schematic perspective view showing the internal structure of the tooth in Embodiment 1. FIG. 2 corresponds to the state of looking through the interior of the tooth in FIG. 1. FIG. 3 is a schematic perspective view showing the structure of a framework portion in Embodiment 1. FIG. 4 is a schematic plan view showing the internal structure of the tooth in Embodiment 1. FIG. 5 is a schematic side view showing the internal

structure of the tooth in Embodiment 1. In FIGS. 1 to 5, the X axis direction corresponds to a longitudinal direction (distal-proximal direction) of the tooth. In FIGS. 1 to 5, the Y axis direction corresponds to a thickness direction of the tooth. In FIGS. 1 to 5, the Z axis direction corresponds to a width direction of the tooth. FIG. 4 is a plan view in the X-Z plane. FIG. 5 is a side view in the X-Y plane.

Referring to FIGS. 1, 2, 4, and 5, a matrix portion 10 constituting the surface of a tooth 1 in Embodiment 1 includes a distal end 10C and a proximal end 19. The matrix portion 10 includes a first surface 11, a second surface 12, a third surface 13, a fourth surface 14, a fifth surface 15, a sixth surface 16, a seventh surface 17, and an eighth surface 18.

Referring to FIG. 5, the first surface 11 and the second surface 12 are each connected to the proximal end 19. The first surface 11 and the second surface 12 are arranged spaced apart from each other in the Y axis direction such that the distance between them decreases as they approach the distal end 10C. The fifth surface 15 and the sixth surface 16 connect the first surface 11 and the second surface 12 to the distal end 10C, respectively. The fifth surface 15 and the sixth surface 16 are arranged such that their distance from each other decreases as they approach the distal end 10C. In the X-Y plane, the angle made by the fifth surface 15 and the sixth surface 16 is larger than the angle made by the first surface 11 and the second surface 12.

Referring to FIG. 4, the third surface 13 and the fourth surface 14 are each connected to the proximal end 19. The third surface 13 and the fourth surface 14 are arranged spaced apart from each other in the Z axis direction such that the distance between them decreases as they approach the distal end 10C. The seventh surface 17 and the eighth surface 18 connect the fourth surface 14 and the third surface 13 to the distal end 10C, respectively. The seventh surface 17 and the eighth surface 18 are arranged such that their distance from each other decreases as they approach the distal end 10C. In the X-Z plane, the angle made by the seventh surface 17 and the eighth surface 18 is larger than the angle made by the third surface 13 and the fourth surface 14. The distal end 10C is a surface (region) that extends linearly in the Z axis direction.

Referring to FIGS. 1, 2, 4, and 5, the proximal end 19 has a recess 10A formed toward the distal end (recessed in the X axis direction). The matrix portion 10 has a through hole 10B formed to penetrate from the third surface 13 to the fourth surface 14. The through hole 10B intersects the recess 10A. That is, the through hole 10B is in communication with the recess 10A.

The tooth 1 is attached, for example, to a bucket (not shown) of a hydraulic excavator. More specifically, a tooth adapter (not shown) is attached to an outer edge of an opening of the bucket of the hydraulic excavator. This tooth adapter has its distal end portion inserted into the recess 10A formed at the proximal end 19 of the tooth 1 (matrix portion 10). The through hole 10B receives a pin (not shown) inserted to penetrate through the through hole 10B. The tooth 1 is thus attached to the bucket via the tooth adapter.

Referring to FIGS. 2 to 5, the tooth 1 includes the matrix portion 10 made of metal, and a framework portion 20 embedded in the matrix portion 10. For the metal constituting the matrix portion 10, cast steel, for example, can be adopted. The cast steel that can be adopted is not particularly limited as long as it has appropriate wear resistance. For example, Cr—Mo cast steel, Cr—Mo-V-W cast steel, Cr—Mo—Ni cast steel, high Mn cast steel, boron cast steel, Cr—Mo—V cast steel, high Cr cast steel, or other low alloy

cast steel may be adopted. Further, cast steel having the component composition of carbon steel for machine structural use or alloy steel for machine structural use specified in JIS standard (for example, S45C or SCM435, as well as manganese steel (SMn), chromium steel (SCr), chromium-molybdenum steel (SCM), or the like containing an equivalent amount of carbon) may be adopted. For the metal constituting the matrix portion 10, cast iron with a higher carbon content than cast steel may also be adopted. The framework portion 20 has a higher hardness than that (of about HV 500) of the matrix portion 10. The framework portion 20 may be made of metal. The metal constituting the framework portion 20 is not particularly limited as long as it has a higher hardness than the metal constituting the matrix portion 10. For example, high hardness steel, such as steel having the component composition of tool steel, bearing steel, spring steel, heat resistant steel, stainless steel, or piano wire as specified in JIS standard, as well as cast iron higher in carbon content can be adopted. The framework portion 20 may be fabricated using one or a combination of two or more of: casting, plastic working, sintering, grinding, pressing, welding, and the like. Forming prior to sintering may be performed, for example, using a 3D printer.

The framework portion 20 has a three-dimensional lattice structure formed with a plurality of bar-shaped members 31 (see particularly FIG. 3). The external shape of the framework portion 20 includes a first surface 21, a second surface 22, a third surface 23, a fourth surface 24, a fifth surface 25, a sixth surface 26, a seventh surface 27, an eighth surface 28, and a distal end 20C. The first surface 21 is along the first surface 11 of the matrix portion 10. The second surface 22 is along the second surface 12 of the matrix portion 10. The third surface 23 is along the third surface 13 of the matrix portion 10. The fourth surface 24 is along the fourth surface 14 of the matrix portion 10. The fifth surface 25 is along the fifth surface 15 of the matrix portion 10. The sixth surface 26 is along the sixth surface 16 of the matrix portion 10. The seventh surface 27 is along the seventh surface 17 of the matrix portion 10. The eighth surface 28 is along the eighth surface 18 of the matrix portion 10. The distal end 20C is along the distal end 10C of the matrix portion 10 (tooth 1).

The matrix portion 10 includes a distal end region 10D that tapers toward the distal end 10C. The framework portion 20 is arranged in the distal end region 10D and has a shape corresponding to an external shape of the distal end region 10D. That is, the external shape of the framework portion 20 follows that of the distal end region 10D. Explained from another perspective, the external shape of the framework portion 20 corresponds to a shape obtained by uniformly reducing the external shape of the distal end region 10D.

In the tooth 1 of Embodiment 1, the three-dimensional lattice-shaped framework portion 20 formed with a plurality of bar-shaped members 31 is embedded in the matrix portion 10. With the framework portion 20 having the three-dimensional lattice structure with high rigidity, deformation of the framework portion 20 is suppressed even if the matrix portion 10 wears down to expose the framework portion 20. As a result, the progress of wear of the tooth 1 is suppressed. Since the framework portion 20 has the three-dimensional lattice structure, the metal constituting the matrix portion 10 fills the interior of the framework portion 20 (the space located between the bar-shaped members 31). This suppresses the framework portion 20 from falling out of the matrix portion 10 even if the matrix portion 10 wears down to expose the framework portion 20. As a result, the progress of wear of the tooth 1 is suppressed. Further, in the tooth 1,

the framework portion 20 is shaped to follow the shape of the surface of the matrix portion 10. This suppresses progress of local wear in the region where the framework portion 20 has a shape that follows the surface of the matrix portion 10. As a result, the wear resistance of the tooth 1 is improved. As such, the tooth 1 in Embodiment 1 is a wear resistant component with improved wear resistance.

Further, the matrix portion 10 of the tooth 1 in Embodiment 1 includes the distal end region 10D which tapers toward the distal end 10C. The framework portion 20 is arranged in the distal end region 10D and has a shape corresponding to the external shape of the distal end region 10D. This enables effective suppression of the wear of the distal end region 10D.

15

Embodiment 2

Another embodiment, Embodiment 2, will now be described with reference to FIGS. 6 to 10. The tooth as a wear resistant component of Embodiment 2 basically has a similar structure and exerts similar effects as in Embodiment 1. However, the tooth of Embodiment 2 differs from that of Embodiment 1 in the following points.

FIG. 6 is a schematic perspective view showing the appearance of a tooth in Embodiment 2. FIG. 7 is a schematic perspective view showing the internal structure of the tooth in Embodiment 2. FIG. 7 corresponds to the state of looking through the interior of the tooth in FIG. 6. FIG. 8 is a schematic perspective view showing the structure of a framework portion in Embodiment 2. FIG. 9 is a schematic plan view showing the internal structure of the tooth in Embodiment 2. FIG. 10 is a schematic side view showing the internal structure of the tooth in Embodiment 2. In FIGS. 6 to 10, the X axis direction corresponds to a longitudinal direction (distal-proximal direction) of the tooth. In FIGS. 6 to 10, the Y axis direction corresponds to a thickness direction of the tooth. In FIGS. 6 to 10, the Z axis direction corresponds to a width direction of the tooth. FIG. 9 is a plan view in the X-Z plane. FIG. 10 is a side view in the X-Y plane.

Referring to FIGS. 6 and 7, in the tooth 1 of Embodiment 2, at least some of the bar-shaped members 31 have their end faces 31A exposed on the surface of the matrix portion 10. Referring to FIG. 8, of the bar-shaped members 31 constituting the framework portion 20 of Embodiment 2, those intersecting the bar-shaped members 31 extending along the first through eighth surfaces 11-18 and the distal end 10C penetrate through them, and their end faces 31A are exposed on the first through eighth surfaces 11-18 and the distal end 10C. The first through eighth surfaces 11-18 and the distal end 10C are flush with the end faces 31A exposed thereon.

With the end faces 31A being thus exposed on the first through eighth surfaces 11-18 and the distal end 10C, the framework portion 20 can contribute to the suppression of the progress of wear from the beginning of the wear progression. Further, in the case of producing the tooth 1 by casting, it is readily possible to place the framework portion 20 in an appropriate position by bringing the end faces 31A of the bar-shaped members 31 constituting the framework portion 20 into contact with a wall surface defining a mold cavity to thereby support the framework portion 20, and then pouring the metal constituting the matrix portion 10 in a molten state.

65

Embodiment 3

Yet another embodiment, Embodiment 3, will now be described with reference to FIGS. 11 to 16. The tooth as a

wear resistant component of Embodiment 3 basically has a similar structure and exerts similar effects as in Embodiment 2. However, the tooth of Embodiment 3 differs from that of Embodiment 2 in the following points.

FIG. 11 is a schematic perspective view showing the appearance of a tooth in Embodiment 3. FIG. 12 is a schematic perspective view showing the internal structure of the tooth in Embodiment 3. FIG. 13 is a schematic perspective view showing the structure of a framework portion and a core in Embodiment 3. FIG. 14 is a schematic perspective view showing the structure of the core in Embodiment 3. FIG. 15 is a schematic plan view showing the internal structure of the tooth in Embodiment 3. FIG. 16 is a schematic side view showing the internal structure of the tooth in Embodiment 3. In FIGS. 11 to 16, the X axis direction corresponds to a longitudinal direction (distal-proximal direction) of the tooth. In FIGS. 11 to 16, the Y axis direction corresponds to a thickness direction of the tooth. In FIGS. 11 to 16, the Z axis direction corresponds to a width direction of the tooth. FIG. 15 is a plan view in the X-Z plane. FIG. 16 is a side view in the X-Y plane.

Referring to FIGS. 11 and 12, in the tooth 1 of Embodiment 3, at least some of the bar-shaped members 31 have their end faces 31A exposed on the surface of the matrix portion 10, as in the case of Embodiment 2. As shown in FIGS. 12 and 13, the tooth 1 of Embodiment 3 further includes a core 40 that is arranged inside the framework portion 20 and is higher in hardness than the framework portion 20. The core 40 may be a sintered body of particles or powder of a hard material such as high-speed tool steel, cemented carbide, or the like. Forming of the core 40 prior to sintering may be performed, for example, using a 3D printer. The core 40 may be fabricated using rolling (including special shape rolling), cutting, forging, casting, or other method in place of, or in combination with, sintering. The core 40 may have, formed on its surface, an overlay that contains particles or powder of high-speed tool steel, cemented carbide, or the like.

Referring to FIGS. 12 to 14, the surface (external shape) of the core 40 includes a first surface 41, a second surface 42, a third surface 43, a fourth surface 44, a fifth surface 45, a sixth surface 46, a seventh surface 47, an eighth surface 48, and a distal end 40C. The first surface 41 is along the first surface 11 of the matrix portion 10 and the first surface 21 of the framework portion 20. The second surface 42 is along the second surface 12 of the matrix portion 10 and the second surface 22 of the framework portion 20. The third surface 43 is along the third surface 13 of the matrix portion 10 and the third surface 23 of the framework portion 20. The fourth surface 44 is along the fourth surface 14 of the matrix portion 10 and the fourth surface 24 of the framework portion 20. The fifth surface 45 is along the fifth surface 15 of the matrix portion 10 and the fifth surface 25 of the framework portion 20. The sixth surface 46 is along the sixth surface 16 of the matrix portion 10 and the sixth surface 26 of the framework portion 20. The seventh surface 47 is along the seventh surface 17 of the matrix portion 10 and the seventh surface 27 of the framework portion 20. The eighth surface 48 is along the eighth surface 18 of the matrix portion 10 and the eighth surface 28 of the framework portion 20. The distal end 20C is along the distal end 10C of the matrix portion 10 (tooth 1) and the distal end 40C of the framework portion 20.

The core 40 has a shape corresponding to the external shape of the framework portion 20. The core 40 is arranged in the distal end region 10D of the matrix portion 10 and has

a shape corresponding to the external shape of the distal end region 10D. That is, the external shape of the framework portion 20 follows that of the distal end region 10D. In the framework portion 20 in Embodiment 3, a space 30D (with no bar-shaped members 31 passing therethrough) is formed which has an opening at an opposite end from the distal end 20C in the X axis direction.

The tooth 1 of Embodiment 3 can be produced in the following manner. First, the end faces 31A of the bar-shaped members 31 constituting the framework portion 20 are brought into contact with a wall surface defining a mold cavity to thereby support the framework portion 20. Next, the core 40 is disposed in the space 30D in the framework portion 20. At this time, the core 40 is supported by the bar-shaped members 31 to be held in an appropriate position. Thereafter, the metal constituting the matrix portion 10 is poured in a molten state. The tooth 1 in Embodiment 3 can be produced through the above procedure.

With the tooth 1 of Embodiment 3 having the core 40, even if the framework portion 20 wears down, the core 40 having an even higher hardness can suppress the progress of wear. In Embodiment 3, the core 40 is shaped to follow the shape of at least a portion of the surface of the matrix portion 10. This suppresses the progress of local wear in the region where the core 40 has a shape that follows the surface of the matrix portion 10. In Embodiment 3, the core 40 being disposed in the distal end region 10D and having the shape corresponding to the external shape of the distal end region 10D can effectively suppress the wear of the distal end region 10D.

It should be noted that in the present embodiment, the framework portion 20 has a higher hardness than that (of about HV 500) of the matrix portion 10 from the standpoint of improving the wear resistance. However, from the standpoint of achieving the function of supporting the core 40, the framework portion 20 may have a hardness comparable to, or lower than, that of the matrix portion 10. The material constituting the framework portion 20 may be, for example, mild steel.

Embodiment 4

An example of application of the present invention to a side protector will now be described as Embodiment 4 with reference to FIGS. 17 and 18. The side protector as a wear resistant component of Embodiment 4 has a structure in which the configuration similar to that of the tooth of Embodiment 3 is applied to the side protector.

FIG. 17 is a schematic perspective view showing the appearance of a side protector in Embodiment 4. FIG. 18 is a schematic perspective view showing the internal structure of the side protector in Embodiment 4. FIG. 18 corresponds to the state of looking through the interior of the side protector in FIG. 17.

Referring to FIGS. 17 and 18, a side protector 100 in Embodiment 4 includes a body portion 111 and a pair of leg portions 112 connected to the body portion 111. The body portion 111 has a bar-like shape that extends along an X axis direction (first direction). The pair of leg portions 112 are connected to respective ends in a width direction (Y axis direction as a second direction) of the body portion 111. The leg portions 112 are arranged to rise from the body portion 111 along a Z axis direction (third direction). Each leg portion 112 has a plate-like shape that extends along the X-Z plane. The pair of leg portions 112 are arranged parallel to each other. The pair of leg portions 112 each have a pair of through holes 113 penetrating the leg portion 112 in the

thickness direction, formed spaced apart from each other in the X axis direction. The through holes 113 of the pair of leg portions 112 are arranged at the same positions in the X axis direction. The side protector 100 is a wear resistant component which is attached, for example, to an outer edge portion surrounding an opening of a bucket (not shown) of a hydraulic excavator to thereby suppress the wear of the outer edge portion. The side protector 100 is fixed to the bucket by fixing members such as pins being inserted into the through holes 113 in the state where a plate-like portion constituting the outer edge of the opening of the bucket is inserted between the pair of leg portions 112.

A matrix portion 110 that constitutes the surface of the side protector 100 in Embodiment 4 includes a pair of end faces 117 which are flat surfaces constituting respective ends in a longitudinal direction (X axis direction) of the body portion 111. The matrix portion 110 further includes a top face 115 which is a flat surface extending in the X axis direction and connecting the pair of end faces 117, a pair of inclined faces 116 which are flat surfaces connected to respective ends in a width direction (Y direction) of the top face 115 and inclined with respect to the top face 115, and a pair of side faces 118 which are flat surfaces connected to opposite sides of the pair of inclined faces 116 from the top face 115 and inclined with respect to the inclined faces 116. The top face 115 is a surface along the X-Y plane. The side faces 118 are surfaces along the X-Z plane. That is, the plane including the top face 115 is orthogonal to the planes including the side faces 118.

Referring to FIG. 18, the side protector 100 includes the matrix portion 110 made of metal, a framework portion 120 embedded in the matrix portion 110, and a core 140, higher in hardness than the framework portion 120, arranged inside the framework portion 120. For the metal constituting the matrix portion 10, cast steel or cast iron, for example, can be adopted as in Embodiments 1 to 3 above. The framework portion 120 may be made of metal, as in Embodiments 1 to 3 above. The metal constituting the framework portion 120 has a higher hardness than the metal constituting the matrix portion 110.

The framework portion 120 has a three-dimensional lattice structure formed with a plurality of bar-shaped members 131, as in Embodiments 1 to 3 above. The framework portion 120 has an external shape that includes a top face 121 and a pair of inclined faces 122. The top face 121 is along the top face 115 of the matrix portion 110. The pair of inclined faces 122 are along the pair of inclined faces 116 of the matrix portion 110. That is, the external shape of the framework portion 120 follows that of the body portion 111. Explained from another perspective, the external shape of the framework portion 120 corresponds to a shape obtained by uniformly reducing the external shape of the body portion 111. Of the plurality of bar-shaped members 131, at least some bar-shaped members 131 have their end portions 131A exposed on a surface of the matrix portion 110 (surface of the side protector 100). The end portions 131A of the at least some bar-shaped members 131 are flush with the surface of the matrix portion 110.

The core 140 may be composed of a material similar to that of Embodiment 3 above. The core 140 has a surface (external shape) that includes a top face 141, a pair of inclined faces 142, and a pair of end faces 143. The top face 141 is along the top face 115 of the matrix portion 110 and the top face 121 of the framework portion 120. The pair of inclined faces 142 are along the pair of inclined faces 116 of the matrix portion 110 and the pair of inclined faces 122 of the framework portion 120. The core 140 has a shape

corresponding to the external shape of the framework portion 120. The core 140 is arranged in the matrix portion 110 corresponding to the body portion 111 and has a shape corresponding to the external shape of the body portion 111.

5 In the framework portion 120, a space with no bar-shaped members 131 passing therethrough is formed to penetrate in the X axis direction, and the core 140 is arranged in the space.

In the side protector 100 of Embodiment 4, the three-dimensional lattice-shaped framework portion 120 formed with a plurality of bar-shaped members 131 is embedded in the matrix portion 110. With the framework portion 120 having the three-dimensional lattice structure with high rigidity, deformation of the framework portion 120 is suppressed even if the matrix portion 110 wears down to expose the framework portion 120. As a result, the progress of wear of the side protector 100 is suppressed. Since the framework portion 120 has the three-dimensional lattice structure, the metal constituting the matrix portion 110 fills the interior of the framework portion 120 (the space located between the bar-shaped members 131). This suppresses the framework portion 120 from falling out of the matrix portion 110 even if the matrix portion 110 wears down to expose the framework portion 120. As a result, the progress of wear of the side protector 100 is suppressed. Further, in the side protector 100, the framework portion 120 is shaped to follow the shape of the surface of the matrix portion 110. This suppresses progress of local wear in the region where the framework portion 120 has a shape that follows the surface 10 of the matrix portion 110. As a result, the wear resistance of the side protector 100 is improved. Furthermore, with the inclusion of the core 140 in the side protector 100, even if the framework portion 120 wears down, the core 140 having an even higher hardness can suppress the progress of wear.

15 Further, in Embodiment 4, with the core 140 being shaped to follow the shape of at least a portion of the surface of the matrix portion 110, progress of local wear is suppressed in the region where the core 140 has a shape that follows the surface of the matrix portion 110. As such, the side protector 20 25 30 35 40 45 50 55 60 65 70 75 80 85 90 95 100 105 110 115 120 125 130 135 140 145 150 155 160 165 170 175 180 185 190 195 200 205 210 215 220 225 230 235 240 245 250 The invention claimed is:

1. A wear resistant component comprising:
a matrix portion made of metal; and
a framework portion embedded in the matrix portion and
higher in hardness than the matrix portion, wherein
the framework portion has a three-dimensional lattice
structure formed with a plurality of bar-shaped
members and has a shape that follows a shape of at least a
portion of a surface of the matrix portion, and
the plurality of the bar-shaped members include a first
bar-shaped member extending along a first direction, a
second bar-shaped member extending along a second
direction intersecting the first direction, and a third
bar-shaped member extending along a third direction
intersecting a plane including the first direction and the
second direction.

12

2. The wear resistant component according to claim 1, wherein at least some of the bar-shaped members have distal ends exposed on the surface of the matrix portion.
3. The wear resistant component according to claim 1, wherein
  - 5 the matrix portion includes a distal end region that tapers toward a distal end, and the framework portion is arranged in the distal end region and has a shape corresponding to an external shape of the distal end region.
4. The wear resistant component according to claim 1, further comprising a core arranged inside the framework portion, wherein the core is higher in hardness than the framework portion.
- 15 5. The wear resistant component according to claim 4, wherein the core has a shape that follows a shape of at least a portion of the surface of the matrix portion.
6. The wear resistant component according to claim 5, wherein the core has a shape corresponding to an external shape of the framework portion.
- 20 7. A wear resistant component comprising:
a matrix portion made of metal;
a framework portion embedded in the matrix portion, and
higher in hardness than the matrix portion; and
a core arranged inside the framework portion and higher
in hardness than the framework portion, wherein
the framework portion has a three-dimensional lattice
structure with a plurality of bar-shaped members and
has a shape that follows a shape of at least a portion of
a surface of the matrix portion,
at least some of the bar-shaped members have distal ends
exposed on the surface of the matrix portion,
the core has a shape that follows a shape of at least a
portion of the surface of the matrix portion,
the core having a has corresponding to an external shape
of the framework portion, and
the plurality of the bar-shaped members include a first
bar-shaped member extending along a first direction, a
second bar-shaped member extending along a second
direction intersecting the first direction, and a third
bar-shaped member extending along a third direction
intersecting a plane including the first direction and the
second direction.
